UNITED STATES PATENT OFFICE.

JOHN E. JOHNSON, OF ELGIN, ILLINOIS, ASSIGNOR TO ILLINOIS WATCH CASE CO., OF ELGIN, ILLINOIS, A CORPORATION OF ILLINOIS.

WATCHCASE.

1,277,937.

Specification of Letters Patent. Patented Sept. 3, 1918.

Application filed November 13, 1917. Serial No. 201,778.

To all whom it may concern:

Be it known that I, JOHN E. JOHNSON, a citizen of the United States, residing at Elgin, county of Kane, and State of Illinois, 5 have invented certain new and useful Improvements in Watchcases, of which the following is a specification.

This invention has general references to watch cases, but relates more particularly 10 to a means of pivotally connecting the bow to the case center.

In watches of the bracelet or wrist style, it is common to secure to the case center oppositely disposed bows or loops to which 15 strap sections or the ends of a bracelet may be attached. It is desirable that the bow should be pivotally mounted on the center so as to be capable of swinging toward the wrist. With the end in view of devising an 20 improved bow for this purpose, and one which will permit of the strap being easily and securely connected thereto, the present invention has been devised. Other objects also will appear from the detailed description 25 to follow wherein reference is made to a preferred embodiment of the invention as illustrated in the accompanying drawing.

Figure 1 is a face view of a bracelet watch of conventional design, securing strap sections being shown attached thereto;

Fig. 2 is an enlarged edge view thereof;

Fig. 3 is a detail of the swinging bow, the parts being disassembled to better exhibit their construction, and

Fig. 4 is an enlarged cross section through the bow in attaching position, its several parts being in assembled relation.

The watch illustrated in Fig. 1 is provided with the usual case center 5 on which is 40 mounted a pendant 6 and two bows 7, each alike, and capable of receiving the looped ends 8 of complementary strap sections 9. Each bow is pivotally connected to a joint 10 which, in the form shown, is provided with 45 feet 11 extended through the walls of the case center and turned to lie on its inner side to secure the joint in place. The joint is formed with the usual cylindrical aperture through which a pin 12 may pass, the 50 pin shown in the drawing being hollow or tubular. The bow comprises two separable ends 13 adapted to aline with each other when inserted within a sleeve 14, and each connected with a tubular portion 15 adapted

to aline with the joint 10. The pin 12, 55 when inserted through the tubular portions 15 and the joint 10, serves as a pintle on which the bow may swing, and its ends 16 may thereafter be spread or upset, as appears best in Fig. 4, to overlie the ends of 60 the tubular portion 15 for the purpose of maintaining the parts of the bow in permanent relation. It will be understood that, during the process of assembling the bow, the sleeve 14 with the ends 13 inserted thereinto, is arranged within the looped end 8 of one of the strap sections 9, so that the strap will be properly and securely attached to the watch.

It should be evident that the present bow 70 can be very simply made, and readily assembled on the watch. The maintaining of the parts in permanent relation is accomplished by the simple expedient of upsetting the ends of the pivot pin 12. By forming 75 the pin hollow or tubular, the turning of the ends may be readily accomplished by the use of a revolving tool having a conical acting head. While I have shown and described a bow construction designed particularly for watches of the bracelet or wrist style, it should be understood that my invention may be applied to other cases as well, and may also be embodied in other forms, and I do not, therefore, desire to be 80 restricted to the exact construction herein shown except as my invention may be limited in its scope by the appended claims as 85 follows.

I claim:

1. A case having a joint secured thereto; a bow comprising end sections in alined relation, alined tubular portions connected with the end sections, and a sleeve adapted to receive the end sections; and a pintle extended through the tubular portions of the bow and through the joint affording a pivotal connection therebetween, substantially as described.

2. A case having a joint secured thereto; 100 a bow arranged for pivotal connection with the joint, the bow being split to provide separable end sections each formed with a tubular portion adapted to aline with the joint and having a sleeve within which its end sections may be received; and a pintle extended through the tubular portion of the bow and through the joint, the pintle being formed 105

at each end with a head serving to afford a pivotal connection between the bow and joint and to maintain the end sections of the bow against separation, substantially as described.

3. A case having a joint secured thereto; a bow comprising end sections in alined relation, alined tubular portions connected with the end sections, and a sleeve adapted 10 to receive the end sections; and a hollow

pintle inserted through the joint and tubular portions of the bow forming a pivotal connection therebetween, the pintle ends being flared to overlie the ends of the tubular portions of the bow, substantially as de- 15 scribed.

JOHN E. JOHNSON.
